[57] **CLAIM**

The ornamental design for a sawhorse table conversion bracket, as shown and described.

DESCRIPTION

FIG. 1 is a side elevation of a sawhorse table conversion bracket showing my new design;

FIG. 2 is a top plan view thereof;

FIG. 3 is a bottom plan view thereof;

FIG. 4 is a right side elevational view thereof;

FIG. 5 is a left side elevational view thereof.

The side opposite to that shown in FIG. 1 is a mirror image thereof.
